UNITED STATES PATENT OFFICE.

FRANK C. RINSCHE, OF DETROIT, MICHIGAN, ASSIGNOR TO BURROUGHS ADDING MACHINE COMPANY, OF DETROIT, MICHIGAN, A CORPORATION OF MICHIGAN.

TIME-SWITCH FOR ADDING-MACHINES.

1,310,965.

Specification of Letters Patent.

Patented July 22, 1919.

Application filed May 15, 1916. Serial No. 97,708.

To all whom it may concern:

Be it known that I, FRANK C. RINSCHE, a citizen of the United States, residing at Detroit, in the county of Wayne and State 5 of Michigan, have invented certain new and useful Improvements in Time-Switches for Adding-Machines, of which the following is a specification.

My invention relates to adding machines 10 which are driven by electric power, and more particularly to such machines where the motor is of a continuously driven rotary type. In the operation of such machines as ordinarily constructed, after the number to be entered is set up in the keys, a finger bar 15 is depressed which throws a clutch between the continuously running motor and the rock shaft of the machine into engagement which causes the operation of the rock shaft by 20 which the number is carried into the machine. Before the machine is operated, the circuit of the motor must be closed and it then continues in continuous operation until the circuit is opened. Where an independ- 25 ently operated switch is relied upon for this purpose it frequently happens that the switch is inadvertently left in the closed position, with the result that there is considerable waste of current and useless wear upon the 30 motor. My invention is designed to furnish a means by which the motor circuit is closed by the depression of the finger bar by which the motor is thrown into gear with or clutched to the machine driving mechanism, 35 and continues closed so long as the machine is operated at the ordinary speed, or until a period elapses after the last operation such as would not ordinarily occur unless the operator had finished his work thereon. When 40 such a period of inaction ensues the timing mechanism of the switch automatically opens the circuit.

I have shown my improvement in connection with an electrically driven machine of 45 the type disclosed in Vincent Patent No. 866,750, issued September 24, 1907, but it will be apparent from the disclosure below that the time switch is applicable to other forms of motor-driven machines, and in fact 50 wherever a rotary motor is employed for driving a machine in which there is a repeatedly manipulated part.

Except in the respects hereinafter noted

the adding machine proper, the motor, the clutch and the means for operating the 55 clutch to cause the motor to drive the adding machine proper are exactly as disclosed in the Vincent patent referred to above, and therefore need be only briefly referred to herein since reference may be had to the 60 specification of said patent for a complete disclosure thereof. Moreover though I have shown in the accompanying drawings and described hereinafter a preferred embodiment of my invention, it is to be understood 65 that the specific disclosure is for the purpose of exemplification only, and that the scope of the invention is set forth in the following claims in which I have endeavored to distinguish it from the prior art so far as 70 known to me without, however, relinquishing or abandoning any portion or feature thereof.

In the accompanying drawings, Figure 1 is a side elevation of so much of an adding 75 machine proper as is necessary to an understand- 80 ing of the invention, having the latter applied thereto, parts being removed and cut away to better disclose the construction; Fig. 2 is a fragmentary view in vertical section on the line 2—2 of Fig. 3, and on an enlarged scale as compared to Fig. 1; Fig. 3 is an elevation partly in section and on an enlarged scale of the driving mechanism shown in Fig. 1, the view being perpen- 85 dicular to the plane of Fig. 1; Fig. 4 is an elevation of the timing mechanism viewed in the same direction as Fig. 2 but at a different stage of operation with parts in section upon a different plane; Fig. 5 is an 90 elevation perpendicular to Fig. 4 of the same construction; Fig. 6 is a detail in section, and Fig. 7 is a detail in perspective on a plane parallel to the plane of Fig. 1. Each 95 part is identified by the same reference character wherever it occurs throughout the several views.

Referring first to Fig. 1, the adding ma- 100 chine proper is indicated at A as of the well known Burroughs type, for the details of which reference may be had to Patents Nos. 504,963 and 505,078, granted to William S. Burroughs, June 12, 1893. The motor B may be of any suitable type and the connec- 105 tions by which the adding machine proper is driven from the motor are shown as

substantially identical with those disclosed in the Vincent patent referred to above. Briefly describing this mechanism the armature of the motor B is mounted upon or connected to a shaft C which carries a worm 7 in mesh with a worm-wheel 8 loosely rotatable upon a shaft 9. (See Fig. 3). The shaft 9 carries at its end a crank-arm 10 which is connected by a link 11 with a crank 12 upon the rock shaft 100 of the adding machine proper. Normally the shaft 9 is at rest even though the motor be running, the worm wheel 8 turning loosely thereon. Provision is made, however, for clutching or locking 15 the shaft 9 to the worm wheel. For this purpose the worm wheel carries upon one side a concentric annulus 13, the outer periphery of which is formed with a series of semi-cylindrical recesses 14, and a disk 15 20 with a peripheral lateral flange 16 is pinned to the shaft 9 at 17 and carries a rotary semi-cylindrical key 18 in a position to be turned into one of the recesses of the annulus 13 when it is desired to lock the worm 25 wheel to the shaft to secure an actuation of the adding machine proper. The key 18 is formed with a mutilated gear 19 which is in mesh with a similar gear formed upon the hub 20 of a lever 21, mounted upon the hub 30 of the disk 15, and revolvable with and independently of said disk. The lever 21 is normally in contact with a stop 22 and when in this position the key 18 presents its flat side to the annulus 13 and the worm wheel 35 is free to turn upon its shaft. The stop 22, which is also semi-cylindrical, is rotated out of engagement with the lever 21 when the adding machine is to be actuated, and this permits the lever 21 to be shifted by a 40 spring into a position to throw the key into engagement with the annulus whereupon the adding machine is actuated. The stop 22 is mounted or formed upon a short shaft 23 which upon its outer end carries a mutilated 45 gear 24 meshing with a similar gear 25 upon an arm 26. (See Fig. 2.) The arm 26 is controlled by the bar 27 which is raised when the finger bar 28 is depressed by the operator. Thus the depression of the finger 50 bar through the rod 27, arm 26 and mutilated gears 24, 25, throws the stop 22 out of the path of the arm 21 and permits an actuation of the machine as heretofore described. Unless the finger bar is maintained 55 depressed the stop 22 intercepts the arm 21 as soon as it has completed a revolution and disengages the parts. The foregoing is an outline of the construction and operation of the mechanism which is fully shown and 60 described in the Vincent patent referred to above.

My invention, as heretofore stated, relates to the means for controlling the supply of current to the motor. The rod 27 through 65 which the clutch is controlled is also the

medium whereby the supply of current to the motor is controlled. A cord 29 carrying a pair of conductors may be attached to an outlet of a supply of current, the conductors at their other ends being connected respectively to the binding posts 30 and 31. To the binding post 30 is also secured the end 32 of one of the conductors leading to the motor, the other of which conductors is connected to the binding post 33. The 75 binding posts 31 and 33 are connected respectively to the plate springs 34, 35, of a knife switch, the movable knife 36 of which is carried by but insulated from an arm 37, pivoted upon a stud 38 secured to the casing 39 of the clutch. A convenient means for securing the knife upon the lever 37 consists in mounting it upon a stud 40, projecting from the face of said lever, a plate spring 41 riveted to the lever at 42 holding 85 the knife in place. The latter is insulated from the supporting lever and spring respectively by insulating washers 43 and collar 44, the spring being slotted at 45 to receive the end of the stud 40 and its surrounding insulation as shown in Figs. 2 and 4. By the construction described the pressure of the plate spring on the washer 90 yieldingly maintains the knife-blade in the proper position for engagement with the 95 plate springs 34, 35.

As best shown in Fig. 2 the arm 37 is pressed in a direction to close the switch by means of the spring 46, the end of which is attached at 47 to a stud on the stationary 100 frame. The arm 37, however, is normally restrained in the open position by a latch 48 which engages a shoulder or abutment 49 upon the arm for this purpose. A spring 50 likewise connected to the stud 47 serves 105 to normally maintain the latch in in-operative position. The tail 51 of the latch extends into the path of movement of a washer 52 secured to the lower end of the rod 27 heretofore described as constituting a part 110 of the clutch controlling mechanism, so that when said rod is raised by the depression of the finger bar 28 it engages and trips the latch 48, permitting the arm 37 to be swung by spring 46 to close the switch. See Fig. 115 2. The closing of the switch completing the circuit through the motor energizes the latter and it continues in operation until the knife switch is again opened in the manner hereinafter described.

Upon the end of the shaft 9 is mounted a snail-cam 53 which partakes of the rotation of the shaft. The cam bears upon a roller 54 carried by a bell-crank lever 55 which is pivoted upon the same stud 38 which forms 125 the fulcrum for the switch arm 37. The bell-crank lever is also connected by a stud 56 to the yoke 57 on the upper end of rod 58 connected to the piston 59 of a dash pot 60 (Figs. 4 and 5). The dash pot is shown as 130

of a familiar form in which openings 61 formed in the piston controlled by a valve 62 permit the ready flow of the oil or other liquid contained in the dash pot cylinder. 5 through the piston when the latter is descending, but prevent the flow of oil therethrough when the piston is ascending, so that the only flow of oil is about the periphery of the piston which is made loose- 10 fitting with this in view. The dash pot cylinder is pivoted at 63 to permit the free movement of the parts. A spring 64 is secured to the bell-crank lever 55 to restore the same to its normal position after having 15 been depressed by the action of the cam upon the roller on said lever, but the action of the dash pot, which is suitably timed for the purpose, retards the upward movement of the bell-crank. In the present instance the 20 dash pot is so constructed as to retard the movement of the lever to the extent of about fifteen seconds.

The latch 48 is pivoted at 65 to an arm 66^a of the T-shaped lever 66 which, like the 25 switch lever 37 and bell-crank lever 55, is pivoted on the stud 38, and is normally maintained in the position shown in Fig. 2 by a spring 67 attached at one end 68 to said lever, and at the other end 69 to the clutch 30 casing 39. The bell-crank lever 55 is provided near the end of its downwardly extending arm with a stud 70 which, when said bell crank approaches the limit of its movement under the influence of the cam, engages the downwardly extending arm 71 of 35 said T-shaped lever 66 and shifts said arm to the left as shown in Fig. 4. This movement of the T-shaped lever raises the catch 48 pivoted thereon sufficiently to permit it 40 to reengage the shoulder 49 upon the switch lever notwithstanding the closed position of the latter. The switch is not opened at this time, however, because a latch 72 is provided for maintaining the lever 71 in the position 45 to the left shown in Fig. 4. The latch 72 is pivoted to a stationary part at 73 and is formed with a pair of shoulders 74, 75, against the former of which inwardly bent end 76 of the arm 71 of the T-shaped lever 50 engages when the device is in its normal position, as shown in Fig. 2, and the other of which engages said arm when it is in the position shown in Fig. 4. It will be seen therefore that the latch 72 maintains the 55 lever 71 in the position shown in Fig. 4, after the stud 70 is withdrawn from contact therewith by reason of the tension of the spring 64 operating against the resistance of the dashpot to raise the laterally extending end of the bell-crank 55, and thus shift the lower end of said bell-crank to the right. In order to release the arm 71 of the T-shaped lever from the latch and permit said lever to return to its normal position, a link 77 is pivoted at its upper end to

the piston rod, upon the screw 56, and has a lost motion connection with the latch 72 by means of a pin 78 and slot 79, which permits the dashpot plunger and bell-crank lever 55 to return to almost normal position, and 70 then to act upon the latch to raise the latter and permit the T-shaped lever 66 to return to its normal position. If the catch 48 is at this time still in engagement with the switch lever, since the spring 67 is sufficiently strong to overpower the spring 46 with the leverages employed, the final movement of lever 66 restores the switch lever to the open position. 75

The adding machine is preferably provided as usual with a clutch connection 80 for attaching the handle for hand-manipulation of the machine when desired. For obvious reasons it is desirable to avoid the accidental operation of the motor when the handle is attached for hand-operation. In order to avoid such accidental operation I provide means operated by the application of the handle to the machine for locking the switch against closing. Such means comprises an arm 81 rigidly secured to the hub 82 of the switch lever, and provided with a laterally extending stud 83 which is straddled by a fork 84 upon the lower end of a vertically shiftable bar 85. The bar 85 may 90 be formed in two sections connected by a screw and slot 86, 87, for adjustment and is guided by a screw 88 upon the frame of the adding machine proper engaging a slot 89 in the offset upper end 90 of said bar. The 95 tip of said bar is bent inwardly and offset laterally at 91 and extends within a notch 92 in a second vertically reciprocating bar 93, the lower end of which is guided by a pivoted connection 94 with a lever 95, and 100 the upper end of which is guided by a screw and slot connection to the frame at 96. The tip of this second vertically sliding bar extends partially into the opening 97 of the clutch member 80, which opening as usual 105 receives a beveled pin upon the handle, said sliding bar being normally maintained in the upper position by means of the spring-operated lever 95. With the parts in the position shown in Fig. 1 the switch lever is 110 freely movable. When, however, the handle is attached to the machine, the conical pin thereon depresses the slide 93, which in turn engages the slide 85 and holds the latter in the depressed position in which the fork 120 thereon engages the stud 83 upon the arm 81, and maintains the latter in its lower position with the switch open.

Referring more particularly to Figs. 1 and 7, the full stroke sector is shown at 104, and 125 the full stroke pawl at 103, these parts being common in the Burroughs type of adding machine in connection with which the present invention is illustrated. In such construction the pawl 103 is normally main- 130

tained in position to engage the sector 104 by a spring 105. It is desirable, however, when the machine is electrically driven that this full stroke mechanism be thrown out of 5 operation. For this purpose the lever 95 has a tail 106 which engages a stud 107 on the full stroke pawl and throws said pawl out of engagement with the sector when the handle is not on the machine, at which time 10 the pawl 93 is in its uppermost position and the lever 95 held in the position shown in Fig. 7 by a spring 108. When, however, the lever 95 is swung about its fulcrum 109 by the application of the handle, as above de- 15 scribed, the tail piece 106 is lifted and the lower branch 110 of a dog 111, to which spring 108 is attached, and which is pivoted on lever 95 at 112, engages the stud 107 and forces the full stroke pawl into position to 20 engage the full stroke sector. The movement of the dog 111 relative to the lever 95 is limited by a stop 113.

A cast metal, or other suitable casing 98 surrounds the switch mechanism just de- 25 scribed, and comprises a boxing 99 and a cover-plate 100. The cover-plate is recessed or notched at 101 upon one of its edges which engage the boxing for the extension of the arm 81 to the outside of the casing, where 30 it is provided with an operating handle or finger piece 102. A shoulder or offset 103 is provided upon the edge of said recess in the cover-plate such that the arm 81, which is of sufficiently resilient material for the pur- 35 pose, may be swung from its normal operative position to a position below said shoulder, and locked there to maintain the switch lever in inoperative position.

The operation of the device has been de- 40 scribed in connection with the description of the various elements thereof, but may be briefly and connectedly repeated as follows:

After a number which it is desired to enter in the machine has been set up, the 45 finger bar 28 is depressed, raising the vertical bar 27 operating the clutch mechanism heretofore described, and tripping the catch 48. The last named operation permits the switch arm 37 to carry the knife into en- 50 gagement with the contacts 34, 35, thus closing the circuit through the motor and operating the latter. This causes the revolution of the snail 53 which engages the roller 54 upon the bell-crank 55, depressing the 55 upper arm of the latter and the plunger of the dash pot. The movement of the bell-crank throws its lower arm to the left and ultimately into engagement with the downwardly extending arm 71 of the T-shaped 60 lever, and the final motion of the bell-crank swings the arm 71 to the left raising the latch 48, thus permitting the latter to again engage the shoulder 49 upon the switch lever. At the same time the latch 72 en- 65 gages the lower end of the T-shaped lever

and maintains it in the left hand position shown in Fig. 4. In the meantime the continued revolution of the snail cam causes the highest part thereof to move from engagement with the roller on the bell-crank, 70 thus permitting the latter to slowly rise retarded by the action of the dash pot. As the bell-crank completes its movement it causes the latch 72 to disengage the arm 71 of the T-shaped lever carrying the catch 48. 75 If in the meantime there has been no actuation of the finger 28, the T-shaped lever when released will carry the switch lever to the open position because of the engagement thereof by the catch 48. If, however, 80 in the meantime there has been a second operation of the finger bar, the catch 48 is again tripped in the manner previously described so that the switch lever is released and any movement of the T-shaped lever 85 toward normal position has no effect upon the switch lever. The motor being still supplied with current thus completes a second revolution, the device operating as before, and this operation is continued until 90 such time as the operator fails to depress the finger bar between the movement of the T-shaped lever from normal position to its return thereto, which period as heretofore pointed out, depends upon the construction 95 of the dash pot. When this occurs the switch lever is thrown to open position cutting out the current from the motor, and the entire device is at rest in normal position.

In the event that the machine should 100 overthrow and the revolution of the cam be carried beyond the normal position to partially actuate the device, the partial operation may be completed by manually throwing the switch lever to closed position 105 by raising the handle 102 thereon. This closes the circuit without distributing any of the other parts of the device.

I claim:

1. In an electrically driven adding ma- 110 chine and in combination with the adding machine proper, a motor for driving the same, rotary means intermediate the adding machine proper and motor for driving the former from the latter, a clutch between the motor and rotary means and a switch for controlling the supply of current to the motor, of a manipulative device for enabling the simultaneous closing of the switch and clutch.

2. In an electrically driven adding ma- 115 chine, and in combination with the adding machine proper, a motor for driving the same, rotary means intermediate the adding machine proper and motor for driving the former from the latter, a clutch intermediate the rotary means and motor and a switch for controlling the supply of current to the motor, of means for opening the switch and devices for preventing the op- 120 125 130

eration of said opening means for a predetermined interval after the closing of the clutch.

3. In an electrically driven adding machine and in combination with the adding machine proper, motor for driving the same, rotary means intermediate the adding machine proper and motor, clutch for coupling the motor to the rotary means and 10 switch for controlling the supply of current to the motor, of a manipulative means set by the operation of the rotary means to open the switch, and a dashpot connected thereto for delaying the opening of the 15 switch.

4. In an electrically driven adding machine, the combination with the adding machine proper, a motor for driving the same, rotary means intermediate the adding machine proper and motor for driving the former from the latter, a clutch for coupling the motor to the rotary means, a manipulative device for controlling said clutch and a switch for controlling the supply of 20 current to the motor, of means controlled by the manipulative device for closing the switch, and means controlled by the operation of the motor for opening the switch a predetermined interval after the clutch has 25 been opened.

5. In an electrically driven adding machine, the combination with the adding machine proper, a motor for driving the same, rotary means intermediate the adding machine and motor for driving the former from the latter, means for coupling the motor to said rotary means, a manipulative device for controlling the last said means and a switch for controlling the motor comprising a movable element, of means for moving the element to close the switch, means normally maintaining said element in open position, means operated by the manipulative device for releasing the last said 40 means, and means controlled by the operation of the motor to restore said element to open position.

6. In an electrically driven adding machine, the combination with the adding machine proper, a motor for driving the same, rotary means intermediate the adding machine and motor for driving the former from the latter, means for coupling the motor to said rotary means, a manipulative device for controlling the last said means and a switch for controlling the motor comprising a movable element, of means for moving the element to close the switch, means for returning said element to open position 45 after the expiration of a predetermined period following the closing of the switch, and means controlled by the manipulative device for preventing the return of said element to open position.

65 7. In an electrically driven adding ma-

chine, the combination with the adding machine proper, a motor for driving the same, rotary means intermediate the adding machine and motor for driving the former from the latter, means for coupling the motor to said rotary means, a manipulative device for controlling the last said means and a switch for controlling the motor comprising a movable element, of means for moving the element to close the switch, means for returning said element to and maintaining it in open position including a catch adapted to engage the same, and means for disengaging the catch when said manipulative device is operated.

8. In an electrically driven adding machine, the combination with the adding machine proper, a motor for driving the same, rotary means intermediate the adding machine and motor for driving the former from the latter, means for coupling the motor to said rotary means, a manipulative device for controlling the last said means and a switch for controlling the motor comprising a movable element, of means for moving the element to close the switch, means including a catch for engaging said element and returning it to open position after the expiration of a predetermined period following the closing of the switch and means for disengaging the catch when said manipulative device is operated.

9. In a device of the class described, a motor, a switch controlling the supply of current to the motor comprising a movable element, means for moving the element to close the switch, means for engaging said element when in closed position and moving it to and maintaining it in open position, and manipulative means for releasing the element from said engagement.

10. In a device of the class described, a motor, a switch controlling the supply of current to the motor comprising a movable element, means for moving the element to close the switch, means including a catch for engaging said element when in closed position and moving it to and maintaining it in open position, and manipulative means for releasing said catch.

11. In a device of the class described, a motor, a switch controlling the supply of current to the motor, comprising a movable element, means for moving the element to close the switch, a lever, means on the lever to engage said element when in closed position, means for moving said lever to carry said element to open position, means operated by the motor to move the lever to engage the element when the latter is in closed position, and a manipulative device for disengaging the element from the lever.

12. In a device of the class described, a motor, a switch controlling the supply of current to the motor, comprising a

- movable element, means for moving the element to close the switch, a lever, means on the lever to engage said element when in closed position, means for moving said lever to carry said element to open position, means operated by the motor to move the lever to engage the element when the latter is in closed position, and a manipulative device for disengaging the element from the lever.
13. In a device of the class described, a motor, a switch controlling the supply of current to the motor comprising a movable contact arm, a spring for moving the same to closed position, means for moving the arm to and maintaining it in open position comprising a lever having a catch for engaging said arm, means for moving the lever to permit the catch to engage the arm in closed position, means for moving the lever after such engagement is effected to restore the arm to open position, and a manipulative device to release the arm from the catch.
14. In a device of the class described, a motor, a switch controlling the supply of current to the motor comprising a movable contact arm, a spring for moving the same to closed position, means for moving the arm to and maintaining it in open position comprising a lever having a catch for engaging said arm, means operated by the motor for moving the lever to permit the catch to engage the arm in closed position, means for moving the lever after such engagement is effected to restore the arm to open position, and a manipulative device to release the arm from the catch.
15. In a device of the class described, a motor, a switch controlling the supply of current to the motor, comprising a movable contact arm, a spring for moving the same to closed position, means for engaging the arm when in closed position and moving it to and maintaining it in open position, means for delaying the return of the arm to open position and manipulative means for releasing the arm from said engagement.
16. In a device of the class described, a motor, a switch controlling the supply of current to the motor, comprising a movable contact arm, a spring for moving the same to the closed position, means for moving the arm to and maintaining it in open position comprising a lever having a catch for engaging said arm, means for moving the lever to permit the catch to engage the arm in closed position, means for moving the lever after such engagement is effected to restore the arm to open position, means for delaying such movement, and manipulative means to release the arm from the catch.
17. In a device of the class described, a motor, a switch controlling the supply of current to the motor, comprising a movable contact arm, and spring for moving the same to closed position, means for moving the arm to and maintaining it in open position, comprising a lever having a catch for engaging said arm, means operated by the motor for moving the lever to permit the catch to engage the arm in closed position, means for maintaining the lever in the position to which it is moved by the motor, a device for releasing the last said means after a predetermined interval of time has expired, means for restoring the lever when released to normal position, and a manipulative device to release the arm from the catch.
18. In a mechanism of the class described, a motor, a switch controlling the supply of current to the motor, comprising a movable contact arm, a spring for moving the arm to closed position, a lever, a catch on the lever normally engaging said arm and maintaining it in open position, a manipulative device for disengaging said catch from the arm, a spring normally maintaining the lever in position to hold the arm in open position when engaged by the catch, means operated by the motor for shifting said lever against the tension of its spring to a position such that the catch will engage the arm when the latter is in closed position, and means for delaying the return of the lever to normal position.
19. In a mechanism of the class described, a motor, a switch controlling the supply of current to the motor comprising a movable contact arm, a spring for moving the arm to closed position, a lever, a catch on the lever normally engaging said arm and maintaining it in open position, a manipulative device for disengaging said catch from the arm, a spring normally maintaining the lever in position to hold the arm in open position when engaged by the catch, means operated by the motor for shifting said lever against the tension of its spring to a position such that the catch will engage the arm when the latter is in closed position, means for restraining the lever in such position, and means for releasing said lever after a predetermined interval and permitting it to return to normal position.
20. In a mechanism of the class described, a motor, a switch controlling the supply of current to the motor comprising a movable contact arm, a spring for moving the arm to closed position, a lever, a catch on the lever normally engaging said arm and maintaining it in open position, a manipulative device for disengaging said catch from the arm, a spring normally maintaining the lever in position to hold the arm in open position when engaged by the catch, a second lever, means driven by the motor for operating the second lever, a spring for restoring the second lever to normal position,

- means on the second lever adapted to engage the first said lever to move the same to a position in which the catch will engage the switch arm while the latter is in closed 5 position, and means for returning the first said lever to normal position after a predetermined interval.
21. In a mechanism of the class described, a motor, a switch controlling the supply of 10 current to the motor comprising a movable contact arm, a spring for moving the arm to closed position, a lever, a catch on the lever normally engaging said arm and maintaining it in open position, a manipulative 15 device for disengaging said catch from the arm, a spring normally maintaining the lever in position to hold the arm in open position when engaged by the catch, a second lever, motor driven means for operating 20 the second lever, a spring for restoring the second lever to normal position, means on the second said lever for engaging the first said lever and shifting the same when the second said lever is operated 25 by the motor, a detent for maintaining the first said lever in shifted position, and means connected to the second said lever for shifting said detent to release the first said lever after a predetermined interval.
22. In a motor-driven adding machine and in combination with the adding machine proper and motor thereof, a switch for controlling the motor circuit comprising 30 an arm carrying the movable member of the switch, a catch for normally maintaining the arm in open position, manipulative means for releasing the catch, means for swinging the arm to closed position when released by the catch, a socket upon 35 the adding machine proper for receiving a handle for operating the same by hand, and means arranged to be engaged by the handle when inserted in the socket to lock said arm in open position.
23. In a motor-driven adding machine 40
- comprising the adding machine proper having a socket for the reception of a handle for hand-operating the same, a motor and connections from the motor for operating the adding machine, a switch controlling 45 the circuit of the motor comprising a movable arm, a catch normally maintaining the arm in open position, a manipulative device for engaging the catch and releasing the arm, means for moving the arm to closed 50 position when released by the catch, a reciprocable member on the adding machine proper, means normally maintaining the same partially within the space occupied by the handle when the latter is connected to 55 the socket whereby the member is adapted to be shifted by the application of the handle to the socket, and means arranged in the path of said member and adapted to be shifted thereby to lock the arm of the 60 switch in open position.
24. In a motor-driven adding machine comprising an adding machine proper, having a socket 80 for the attachment of an operating handle, a motor and connections 70 from the motor for driving the adding machine proper, a switch for the motor comprising a movable arm, means tending to move the arm to closed position, a catch normally engaging the arm and maintaining 75 it in open position, a manipulative means adapted to engage the catch and release said arm to permit the latter to go to closed position, a reciprocating member 85 adapted to be moved to lock said arm in 80 open position, and a slide 93 adapted to engage said locking member and so arranged with respect to the socket as to be engaged by the handle when inserted in the socket, and shifted to force the locking member to 85 operative position.

FRANK C. RINSCHE.
